FIG. 7

FIG. 8

FIG. 1 is a front perspective view of one form of a calculating machine showing my new design;

FIG. 2 is a rear elevational view thereof;

FIG. 3 is a top plan view thereof;

FIG. 4 is a left side elevational view thereof;

FIG. 5 is a front perspective view of another embodiment of the calculating machine shown in FIG. 1, wherein the paper holding upper casing extends substantially from side to side rather than stopping short of the sides and wherein the finger lift openings are at the sides rather than front and back;

FIG. 6 is a rear elevational view thereof;

FIG. 7 is a top plan view thereof; and

FIG. 8 is a left side elevational view thereof.

The essential features of my design reside in the portions shown in solid lines on the drawing.

This application is a continuation-in-part of my pending design patent application Serial No. 70,036, filed May 8, 1962, which is now abandoned.

I claim:

The ornamental design for a calculating machine, as shown and described.
